UNITED STATES PATENT OFFICE.

JAMES H. WAGENHORST, OF JACKSON, MICHIGAN.

CABINET FOR ARC LAMPS.

Application filed March 4, 1926. Serial No. 92,202.

My invention relates to improvements in arc lamps, and has to do, more particularly, with the construction of cabinets for arc lamps and the means for housing and supporting the various operating parts of the lamp in the cabinet.

The chief object of my invention is to provide a cabinet of cheap and simple construction and forming a stiff and rigid structure which will withstand hard usage and still keep its shape.

A further object of my invention is to provide an arc lamp and cabinet, in which the operating parts of the lamp are supported by the cabinet itself as distinguished from prior structures in which the cabinet serves merely as a housing for the lamp. A further object of my invention is to provide a construction in which the supporting elements for the operating parts of the lamp help to reinforce and stiffen the cabinet.

A further object of my invention is to provide a construction in which the rheostat and control parts for operating the lamp are housed so as to be protected from the direct heat of the arc, and in which the construction provides means for cooling these parts.

A further object of my invention is to provide a cabinet for an arc lamp which gives a relatively wide angle of light propagation.

A further object of my invention is to provide an arc lamp and cabinet of such a nature that the lamp and cabinet can be collapsed to a comparatively flat package for the purpose of transportation. This is particularly advantageous in connection with the use of such lamps in motion picture studios, in which it is frequently necessary for the operator to pack up the lamps and transport them to a location which is to be photographed.

A further object of my invention is to provide a cabinet construction for arc lamps which provides a support, at the proper distance from the arc, for a diffusing curtain or screen.

Further objects, and objects relating to details and economies of construction and operation, will definitely appear from the detailed description to follow. In one instance, I have accomplished the objects of my invention by the devices and means set forth in the following specification. My invention is clearly defined and pointed out in the appended claims. A structure constituting a preferred embodiment of my in-

vention is illustrated in the accompanying drawings, forming a part of this specification, in which:

Fig. 1 is a perspective view of a lamp embodying my invention mounted upon a stand in position for use, the curtain being shown drawn across the front of the lamp to diffuse the light coming therefrom.

Fig. 2 is a view in front elevation of the cabinet and lamp, part of one of the cover plates being broken away.

Fig. 3 is a vertical, sectional view through the cabinet and lamp.

Fig. 4 is a horizontal, sectional view, taken on the line 4—4 of Fig. 2.

Fig. 5 is another horizontal, sectional view, taken on the line 5—5 of Fig. 2, the cover for the compartment housing the solenoid and other control parts being removed.

Fig. 6 is a perspective view showing the back of the cabinet, and

Fig. 7 is a detail, sectional view, taken on the line 7—7 of Fig. 3.

In the drawings, the same reference numerals refer to the same parts throughout the several views.

In general I accomplish the objects of my invention by providing a sheet metal cabinet of substantially rectangular shape, that is, having a back wall and side and end walls. The central portion of the back wall, however, is pressed rearwardly forming a rearwardly-extending central depression opposite the electrodes. I propose to provide transverse brace bars fastened to the portions of the back wall on opposite sides of the central depression and extending across said depression, which brace bars not only serve to stiffen the whole structure but also form supports for the lower or stationary electrodes, for the electrode guides through which the upper or movable electrodes work, and for the feeding mechanism for the electrodes. I have further purposed to mount the feeding solenoid and its dash pot at one side of the cabinet in the space between the side portion of the back wall and one of the side walls, and to mount the rheostat in a similar space at the opposite side of the cabinet. These spaces may be confined by removable lids or covers inclined at an angle and cutting off the corner portions of the cabinet, forming separate compartments in which these operating parts are housed. I propose to provide the portions of the end walls of the cabinet forming the tops and

the clamping members 48 mounted upon the binding posts 49 carried by the bar. A similar brace bar 50 of angle cross-section extends across the central portion of this depression in the rear wall of the cabinet, the horizontal leg of this angle member being cut away, as shown in Fig. 4, leaving flat ends on said bar, which lie against the rear wall portions 23 and 24 and are secured thereto by the bolts 51. Like the bar 45 this brace bar 50 serves to strengthen the structure and it also provides a support for the guide members 52, of insulating material, which are bolted to the horizontal flange of said angle bar. These guide members 52 guide and support the movable electrodes 53, and the feeding clutches 54, which engage one electrode in each of the two pairs of upper electrodes, are connected to the vertical legs 55 of the yoke 56, with the lower ends of said legs extending through holes in said insulating guide members 52. A similar angle brace bar 67 extends across the central depression in the rear wall near the upper end thereof, being secured to the portions 23 and 24 of the cabinet by means of the bolts 68. This angle bar 67 carries a pivot pin 66 on which the lever 59 is fulcrumed. The yoke 56 is clamped within a saddle member 57 which is pivoted on the inner end of the lever 59 by means of the pin 58. A yoke 60 is suspended from the outer arm of the lever 59 and connected through a spring 61, to a solenoid armature 62 working in the solenoid 63, this yoke being also connected with a plunger working in the dash pot 65. The feeding solenoid 63 is mounted in a bracket 64, fastened to the side wall 25 of the cabinet. A resistance coil, or rheostat, 69 is mounted at the opposite side of the cabinet, as shown in Figs. 2 and 4.

A compartment of triangular cross section, housing the feeding solenoid and its dash pot, is formed at one side of the cabinet by means of a removable cover 70, which, at one end, is folded upon itself and bent to form a flange 71 lying parallel to the rear wall portion 24 of the cabinet and secured thereto by the bolts 72. The forward edge of this cover 70 is bent upon itself, forming a groove 73, which receives the forward edge of the side wall 25. This cover is secured in place by means of the bolts 43, which also form the hinge connections for the wings 34. This portion of the end wall 28 forming the bottom of this compartment is provided with a number of ventilating holes 75 and the corresponding portion of the end wall 27 forming the top of the compartment is provided with ventilating holes 76, so that a current of air may pass through the holes 75 and up through the compartment in which the feeding solenoid, and its dash pot and connec-

tions with the feeding lever, are housed. In this way, these parts may be kept cool by the current of air ascending through this compartment, as through a flue. A similar cover 70, similarly connected to the cabinet, is provided at the other side thereof. The rheostat 69 is mounted upon this removable cover 70 by means of the block 95 secured to this cover and provided, at intervals, with binding posts 73 to which the wires may be connected. The bottom and top walls of this compartment are also provided with ventilating holes 75 and 76 so that this compartment containing the rheostat may be cooled by the action of a current of air ascending through it as through a flue. These cover plates 70 not only form separate compartments at the sides of the cabinet but also strengthen and reinforce the cabinet materially since, in effect, they form trusses at the sides thereof.

The bracket 17 for supporting the cabinet includes the vertical legs 77, the ends of which are turned laterally at 99 and extend through the side walls 25 and 26 of the cabinet into bearings 98 carried by brackets bolted to the rear wall portions 23 and 24. The bracket 17 may be formed of two rods, bent to the form shown in Fig. 2, with their adjacent ends turned downwardly, as at 78, and lying against each other, and with a pin 79 extending transversely therethrough. The two end portions 78 of this bracket constitute, in effect, a post which fits in the upper end of the standard 15 and supports the lamp upon said standard. The cabinet may be kept from turning upon its bearings on the inturned ends 99 of the arms 77 of the bracket by means of the set screws 80 extending through the rear wall of the cabinet and engaging said inturned ends.

Brackets 81 are fastened to the end walls 27 and 28 of the cabinet, and provided with openings receiving the pins at the ends of the roller 82 on which the diffusing screen or curtain 83 is mounted. This curtain is adapted to be drawn from the roller 82 across the front of the cabinet and across the frames mounted on the wings 34, as indicated by dotted lines in Fig. 4, and is to be held in place across the front of the cabinet by means of clips 84 mounted on the rear wall portion 24.

A porcelain thimble 85 is provided in the lower portion of the inclined back wall 20 of the cabinet and, through this thimble, extend the wires 86 and 97 which are connected to opposite sides of a line leading to a suitable source of electric current. The wire 86 extends through another porcelain thimble 87 fixed in the lower portion of the cover plate 70 for the compartment containing the feeding solenoid, and extends up to and is connected to the solenoid 63, at 88. A wire 89,

- 1 leading from the upper end of the solenoid 63, extends through a similar porcelain thimble 90 in the cover plate 70 and is connected to the electrode holder and guide 91, which is clamped on the upper ends of the pair of upper electrodes nearest to the compartment containing the feeding solenoid. The similar electrode holder and guide 93, clamped on the upper ends of the other pair of movable electrodes, is connected by a wire 94 to one of the binding posts 73 of the rheostat 69, for instance, to the upper one of these binding posts, as shown in Fig. 2. The wire 97 is connected to another of the binding posts 73, for instance, the lower one shown in Fig. 2, and extends out through the porcelain thimble 85. The clamping members for the lower electrodes are electrically connected by the wire 92. An asbestos mat 100 may be fastened on the bottom wall of the cabinet under the lower ends of the stationary electrodes so as to catch any sparks or ashes falling from the burning arcs.
- 2 The construction of the mechanism for feeding the electrodes to and from each other, so as to draw and maintain the arcs, is not described in detail in this application as it forms the subject-matter of another application entitled Arc lamps, filed by me in 30 the Patent Office of even date herewith.
- 3 I am aware that the particular construction disclosed in this application is susceptible of considerable variation without departing from the spirit of my invention and, 35 therefore, I claim my invention broadly as indicated by the appended claims.
- 4 What I claim is:
- 5 1. A cabinet for an arc lamp having stationary and movable electrodes and feeding 40 mechanism therefor, comprising rear, side and end walls, the rear wall having a central rearwardly extending depression therein, and a plurality of brace bars secured to the cabinet and extending across said depression, 45 said brace bars reinforcing the cabinet and supporting the electrodes and the feeding mechanism therefor.
- 6 2. In an arc lamp provided with stationary electrodes, a cabinet having rear, side and 50 end walls, said rear wall having a central rearwardly extending depression, and a brace bar connected to portions of said rear wall at the sides of said depression and extending across said depression, said brace bar reinforcing the cabinet and supporting the stationary electrodes of the arc lamp.
- 7 3. In an arc lamp, the combination with 55 stationary and movable electrodes and operating mechanism therefor, of a cabinet having rear, side and end walls and a central rearwardly extending depression in said rear wall, and a brace bar connected to the portions of said rear wall adjacent the sides of 60 said depression and extending across said depression, said brace bar reinforcing the
- 8 4. In an arc lamp, the combination with stationary and movable electrodes and feeding 65 mechanism therefor, of a cabinet having rear, side and end walls, the rear wall having a central rearwardly extending depression therein, and a brace bar fastened to the portions of said rear wall at the sides of said depression and extending across the same, 70 the said brace bar reinforcing the cabinet and supporting the feeding mechanism for the movable electrodes.
- 9 5. In an arc lamp, the combination with stationary and movable electrodes and a lever 75 for feeding the movable electrodes with respect to the stationary electrodes, of a cabinet having rear, side and end walls and a central rearwardly extending depression in said rear wall, and a brace bar fastened to the portions of said rear wall at the sides of said depression and extending across the same, 80 the said brace bar reinforcing the cabinet and supporting the feeding mechanism for the movable electrodes.
- 10 6. In an arc lamp, the combination of 85 stationary and movable electrodes, means for feeding the movable electrodes with respect to the stationary electrodes, and a cabinet supporting and housing said parts and provided with compartments at the two sides 90 thereof for housing the electrical mechanism controlling the feeding of the movable electrodes.
- 11 7. In an arc lamp, the combination with 95 stationary and movable electrodes, and feeding mechanism therefor including a solenoid, of a cabinet housing and supporting said operating parts of the lamp and a compartment formed at one side of said cabinet and housing the feeding solenoid.
- 12 8. In an arc lamp, the combination with 100 stationary and movable electrodes and a rheostat connected in circuit with said electrodes, of a cabinet housing and supporting said parts of the lamp and a compartment 105 provided at one side of the cabinet in which the rheostat is housed.
- 13 9. In an arc lamp, the combination of stationary and movable electrodes, feeding 110 mechanism for said movable electrodes including a solenoid, a rheostat connected in circuit with said electrodes, and a cabinet housing and supporting the operating parts of said lamp and having a compartment at one side thereof housing the feeding solenoid 115 and co-operating parts and a compartment 120 at the other side housing the rheostat.
- 14 10. The combination of a cabinet for arc 125 lamps having rear, side and end walls and a central rearwardly extending depression formed in said rear wall, and a removable cover plate extending diagonally from the front edge of one side wall to the rear wall adjacent the edge of the central depression therein, said cover plate bracing the cabinet 130

and forming a compartment at one side thereof adapted to house certain of the operating parts of the lamp.

11. In an arc lamp, the combination of 5 stationary and movable electrodes, feeding mechanism therefor including a solenoid connected in an electric circuit with said electrodes, a cabinet having rear, side and end walls, and a removable cover plate forming, with the rear, side and end walls a compartment within which said solenoid is mounted, the portions of the end walls of the cabinet forming the upper and lower ends 10 of said compartment having openings to permit the circulation of air through the compartment for cooling the solenoid. 15

12. In an arc lamp, the combination of stationary and movable electrodes, a rheostat included in the electric circuit with said electrodes, a cabinet having rear, side and end walls, and a removable cover plate forming with said walls a compartment in which said rheostat is mounted, the portions of the end walls forming the top and bottom of said 20 compartment having openings therein for the purpose of permitting the circulation of air through the compartment for cooling the rheostat. 25

13. In an arc lamp, the combination of 30 stationary and movable electrodes, a rheostat connected in an electric circuit with said electrodes, feeding mechanism for the movable electrodes including a solenoid connected in circuit therewith, a cabinet housing 35 and supporting the operating parts of said lamp and including rear, side and end walls, and removable cover plates forming, with said walls, compartments at the sides of the lamp, one of said compartments housing the 40 solenoid and the other the rheostat, the end walls of said cabinet forming the top and bottom of said compartment having openings therein to permit the circulation of air through said compartments. 45

14. In an arc lamp, the combination of 50 stationary and movable electrodes, feeding mechanism for said movable electrodes including a solenoid connected in circuit therewith, a cabinet housing and supporting said parts and including a rear wall with a central, rearwardly-extending depression, and side and end walls, and a removable cover plate extending diagonally from the front edge of the side wall to said rear wall adjacent the edge of the central depression therein, said cover plate bracing the cabinet and forming a compartment within which said solenoid is mounted, the portions of the end walls forming the top and bottom of 55 said compartment having holes formed therein to permit the circulation of air through said compartment for cooling the solenoid. 60

15. In an arc lamp, the combination of 65 stationary and movable electrodes, a rheostat

connected in an electric circuit with said electrodes, a cabinet housing and supporting said parts and provided with rear, side and end walls, said rear wall having a central, rearwardly-extending depression therein, 70 and a removable cover plate extending diagonally from the front edge of one side wall to the rear wall, adjacent the side of the central depression therein, said cover plate bracing said cabinet and forming a compartment 75 within which said rheostat is mounted on the inner wall of said cover plate, and the end walls of said cabinet being provided with holes in position to permit the circulation of air through said compartment. 80

16. In an arc lamp, the combination of stationary and movable electrodes, feeding mechanism therefor including a solenoid connected in circuit with said electrodes, a rheostat also connected in said circuit, a cabinet 85 housing and supporting the parts of said lamp and including rear, side and end walls, said rear wall having a central, rearwardly-extending depression therein, and a pair of removable cover plates extending diagonally 90 from the front edges of the side walls to the portions of the rear wall adjacent the sides of said central depression, said cover plates bracing the cabinet and forming compartments at the sides thereof housing said solenoid and rheostat, respectively. 95

17. The combination of a cabinet for arc lamps having rear, side and end walls, and light deflecting wings hinged to the front portions of the end walls of said cabinet. 100

18. The combination of a cabinet for arc lamps comprising rear, side and end walls, light deflecting wings hinged to the front portions of the end walls of said cabinet and frames carried by said wings and extending 105 substantially perpendicular thereto, said frames being adapted to engage and hold away from the front of the lamp a light diffusing curtain or screen. 110

19. The combination of a cabinet for arc lamps having rear, side and end walls, and light deflecting plates hinged to the front portions of the end walls of said cabinet, and frames secured to each of said plates or wings and comprising leg portions extending 115 at right angles to the body of said wings and an inclined portion connecting the upper ends of said leg portions, one of said leg portions being extended through the wing and extended parallel to one edge thereof, 120 the end portion of said wing being wrapped around said portion of the frame, and the end of said portion of the frame being bent to form an eye co-operating with a bolt passing through the side of the cabinet to form a 125 hinge member for hinging the wing to the cabinet. 130

20. In an arc lamp, the combination of movable and stationary electrodes, feeding mechanism therefor, a cabinet housing and

supporting said parts, brackets fastened to the end walls of said cabinet, a curtain roller supported by said brackets, and a diffusing curtain mounted on said roller and adapted to be drawn across the front of the cabinet to diffuse the light coming from the arc.

21. In an arc lamp, the combination of stationary and movable electrodes, feeding mechanism therefor, a cabinet housing and supporting said parts, brackets carried by said cabinet, a curtain roller supported by said brackets, light deflecting wings hinged to the front portions of the end walls of said cabinet, frames carried by said wings, and a diffusing curtain mounted on said roller and adapted to be drawn across the front of said

cabinet and across said frames to diffuse the light coming from the arc.

22. In an arc lamp, the combination of stationary and movable electrodes, feeding mechanism therefor, a cabinet housing and supporting the parts of said lamp and including rear, side and end walls, bearings mounted within the cabinet upon said rear wall, and a supporting bracket for said cabinet and lamp provided with arms and laterally turned studs at the ends of the arms, said studs extending through the side walls of said cabinet and being journaled in the said bearings.
